Inventor:

UNITED STATES PATENT OFFICE.

JOSEPH M. MILLER, OF CHICAGO, ILLINOIS.

FIRE-EXTINGUISHER.

1,190,316.

Specification of Letters Patent. Patented July 11, 1916.

Application filed February 8, 1915. Serial No. 6,790.

To all whom it may concern:

Be it known that I JOSEPH M. MILLER, a citizen of the United States of America, and a resident of Chicago, county of Cook, and 5 State of Illinois, have invented certain new and useful Improvements in Fire-Extinguishers, of which the following is a specification.

In hand fire extinguishers of the type 10 similar to that shown in my Patent No. 1,018,514 granted February 27, 1912, where the liquid chemical is pumped from the container through a flexible hose connected near the top of the container, it has been found 15 that upon setting the extinguisher aside after using, and dropping the hose without first taking the precaution of draining the liquid in the hose back into the container, the liquid has been siphoned out of the 20 container.

The main object of this invention, therefore, is to provide an improved construction of fire extinguishers of this kind, whereby the liquid in the discharge passages will be 25 automatically drained when the extinguisher is set aside after being used, and whereby the accidental siphoning out of the contents of the container is impossible.

An illustrative embodiment of this invention is shown in the accompanying drawings, in which:

Figure 1 is an elevation of an improved fire extinguisher of this type, a portion of the container and discharge pipe being 35 broken away at the top to more clearly show the arrangement for draining the discharge passages. Fig. 2 is a fragmentary detail of the hook by means of which the pump handle is locked so that it may be used 40 for carrying the extinguisher.

In the construction shown in the drawings, the extinguisher comprises a container 1 provided with handles 2 and 3 for carrying and manipulating it, and provided with 45 a pump which extends longitudinally through the interior of the casing from the top to a point adjacent to the bottom.

The pump comprises a cylinder 4 in which is mounted a piston rod connected at its upper end to a handle 5 by means of which the pump is operated. The cylinder 4 serves as the discharge pipe and suitable valves are arranged to cause the proper discharge of the liquid under pressure. A branch discharge pipe 6 is connected to the upper end

of the cylinder 4 and extends transversely out through the top of the container. The pipe 6 terminates in a downwardly facing elbow and has connected thereto a flexible hose 7 which normally hangs vertically and by means of which the liquid is directed when being discharged. The pump cylinder 4, branch pipe 6, and hose 7 constitute a substantially inverted U-shaped discharge passage for the fluid and is normally unobstructed in that there is always open communication from inlet to outlet.

The branch discharge pipe 6 is provided with an aperture or vent passage 8 located within the container, and providing communication therewith. The aperture 8 is comparatively small, and is located so that when the operation of the pump is stopped, air will be admitted to the pipe 6, permitting the liquid remaining in the hose to drain out through the nozzle 9 without setting up a siphonic action. During the operation of the pump a small jet of the liquid will, of course, pass through the aperture back into the container, but the quantity thereof will be exceedingly small and will not interfere with the efficient operation of the pump or the effectiveness of the extinguisher.

The container 1 is provided with a filling opening normally closed by a plug 11. This opening is located below the level of the branch 6 so that in filling the container, there is no danger of the level of the liquid rising above the branch 6 and thereby running out through the hose 7 so as to start a siphoning action.

In order that the handle 5 may also serve as a means for carrying the extinguisher, and cannot be unintentionally operated, a hook 10 is hinged at the top of the casing in position to engage the handle as shown in Fig. 2.

Although but one specific embodiment of this invention has been herein shown and described, it will be understood that some of the details of the construction shown may be altered or omitted without departing from the spirit of this invention as defined by the following claim.

I claim:

The combination of a container, a pump extending longitudinally into said container, a transversely disposed branch leading from said pump to the exterior of said container near the top thereof, and a hose connected

105

110

to said branch, the communication between said pipe and branch and hose being normally open, said branch having a vent located therein within said container, said 5 container having a filling opening located below the level of said vent.

Signed at Chicago this 5th day of February 1915.

JOSEPH M. MILLER.
